UNITED STATES PATENT OFFICE

GEORGE E. ROWE, OF BOSTON, MASSACHUSETTS, ASSIGNOR OF ONE-HALF
TO NATHANIEL B. STEVENS, OF SAME PLACE.

DESIGN FOR A CASTER.

SPECIFICATION forming part of Design No. 23,688, dated October 16, 1894.

Application filed August 24, 1894. Serial No. 521,243. Term of patent 14 years.

To all whom it may concern:

Be it known that I, GEORGE E. ROWE, of Boston, in the county of Suffolk and State of Massachusetts, have invented a certain novel

5 Design for Casters, of which the following is a specification, reference being had to the accompanying drawing, forming a part thereof.

The drawing shows a perspective view of my design, the leading feature of which is 10 the body portion (b) of the caster, having a tapering form decreasing in size from the base to the top, and provided on its sides with apertures, (b²) (b³) (b⁷), and at its base with rectangular extensions (b') having openings,

15 and provided at its top (b⁴) with an ornamental figure, crest or finial. The body portion (b) is shown as resting upon a suitable foot (a).

I claim—

20 The design for casters, substantially as herein shown and described.

In testimony whereof I have signed my name to this specification, in the presence of two subscribing witnesses, this 20th day of August, A. D. 1894.

GEORGE E. ROWE.
